FLOOR MAT CONSTRUCTION

John H. McClelland, Ferndale, Mich.

Application December 24, 1937, Serial No. 181,623

5 Claims. (Cl. 20—78)

The object of my invention is to construct a floor mat of the link type wherein the individual links of the mat are secured together in an improved manner.

5 A further object of my invention is to provide link type floor mats which will be uniform in size, especially in width. My improved floor mat is adapted to be manufactured in large quantities to very close dimensions. This feature is 10 of great importance because my mat is intended to be used with a pan shaped, molded rubber container in which the mat is resiliently secured by the edges of the container. These containers are, of course, molded to a uniform size and only 15 the rim resiliently grips the edges of the mat to retain same therein. All other link mats known to the applicant vary in width to such an extent that they cannot be commercially manufactured for use in the above-mentioned containers, some being too loose and others so wide 20 that they cannot be inserted without breaking the edges.

Still a further object of my invention is to provide a link type floor mat which may be rolled up, like a rug, and which will, when so rolled, possess sufficient bending strength that it may be lifted by its center portion without permanently bending any of the link pivot pins. The lateral bending resistance of link type mats is obtained 30 solely by the link pivot pins which have heretofore been formed only as solid rods. When such rods were formed sufficiently large to provide an appreciable bending resistance, their weight necessarily increased to thereby increase the 35 force tending to bend the rods when the mat was lifted by one end or by the center. It is extremely important that the rods do not receive a permanent bend when so lifted because in such case the mat will not lay flat when unrolled. In 40 my improved construction, I provide tubular pivot pins which function to materially increase the lateral strength of my mat without increasing its weight over the former solid rod type construction. Thus a wider mat may be handled 45 by one person than was possible with the older type mats.

Still a further object of my invention is to provide an improved means for preventing axial movement of the link pivot pins relative to the 50 links.

With these and other objects in view, my invention consists in the arrangement, construction and combination of the various parts of my improved mat, as described in the specification,

claimed in my claims, and illustrated in the accompanying drawing, in which:

Figure 1 is a plan view section of my improved mat and container for holding same.

Figure 2 is a full size plan view of one corner 5 portion of the mat and container shown in Figure 1.

Figure 3 is a sectional view, taken upon the line 3—3 of Figure 2.

Figure 4 is a sectional view, taken upon the 10 line 4—4 of Figure 2, and

Figure 5 is a sectional view, similar to Fig. 4, but showing an alternate means for retaining the links upon the link pivot pins.

Referring to the accompanying drawing, I 15 have shown the molded rubber container in which my improved mat is adapted to be inserted. This container comprises a flat bottom portion 10 having a rim 11 molded integrally therewith which extends around the bottom 10 20 to form a rectangular container. The rim 11 is tapered from a thin section at its outer edge to a relatively thick section at its inner edge and the wall 12 which extends upwardly from the bottom 10 to the inside edge of the rim is molded 25 to extend diagonally inwardly.

The purpose of the aforementioned container is to form a collector for water, dirt and the like so that the container with a mat therein may be laid over a polished floor or rug and still 30 dirt or water which is caught by the mat will not be allowed to filter through to the rug, or the floor. My improved mat is adapted to be built in a shape to fit the aforementioned container.

It is required that the mat must be readily removable from the container so that the dirt and water collected therein may be conveniently cleaned out without disturbing the container. Further, the mat should be held within the container so that it will not accidentally crumple up, to thus form an obstruction over which, people might trip. To form such a mat I provide a plurality of molded rubber links 13, each of which has a width slightly greater than its thickness, 40 both sides of which have traction grooves 14 extending crosswise therethrough. The ends of the links 13 are rounded and provided with spaced parallel openings 15 extending therethrough along the axes of their rounded ends. 45

The links are preferably molded in several colors so that they may be assembled to form a variety of patterns or designs. In assembling, the links are arranged crosswise in rows with each link spaced from the next the width of one 50 55

link. The rows of links are interlocked or dovetailed together so that the openings in the links in one row are axially aligned with the openings in the links in the adjacent rows, respectively.

5 The applicant is aware that mats of this same general description have been provided in the past, but all of these differ from the construction herein shown in that wires usually of hair-pin shape were inserted through the aligned openings in the links. The open ends of these hair-pins were bent in opposite directions and usually joined to the adjacent hair-pins by sleeves. This construction has the disadvantage that the links adjacent to the ends of each hair-pin are deformed, due to the bending of the hair-pin at the ends. Further, for the reason that the open ends of the links must be bent after the links have been assembled thereon, a uniform bend cannot be made, as would be possible could the 10 hair-pin be held in a die against which the ends could be bent. Consequently, all of such mats have varied materially in width. If such mats are used with the above-described containers, the rims of the container will only loosely fit some 15 of the mats while others will be so large that the user cannot conveniently remove and reinsert the mat when the container is being cleaned.

In the applicant's construction, this defect is overcome by providing tubular pivot pins 16 which extend through each row of aligned openings 15. The ends of the pins 16 are flush with the outer edges of the link assembly. A ferrule or grommet 17 is inserted in each edge link adjacent to the ends of the tubes 15 and drive screw 18 is driven into the ends of these tubular pins, as shown in Figure 3. The tubes 15 are not tapped, it only being required that the screws be of such size that they may be conveniently driven in place by a light blow from a hammer.

40 The screws 18 are provided with relatively large heads 19 which prevent the ferrules 17 from sliding off the tubes. Inasmuch as the tubes 16 may be inexpensively cut to a uniform length, it will be apparent that mats formed with such tubes will be of uniform width.

45 It may be desired, where many mats are to be produced and the cost of special machines is not therefore objectionable, to provide the alternate means, shown in Figure 5, for preventing the links from sliding off the tubular pins. In this construction the tubes 16 are formed somewhat longer than the width of the mat and the ends thereof flanged outwardly over the grommets 17 to form flanges 20. This method dispenses with the screws 18 but requires the use of a special flanging machine.

Several unexpected advantages arise from the use of either construction above described. One of these advantages is that, due to the greater rigidity against bending of a tubular pivot over a wire pin of the same weight, the mat constructed with such tubular pivots is much stiffer laterally than a mat of the same weight having wire pivots. My improved mat may thus be removed from the container, rolled up and taken out to be cleaned with far less danger of bending permanently any pivot. Of course, the older type of wire pivot pins may be made with a diameter as large as the tubes 16 and they 70 will have an equivalent rigidity, but in this case the free ends of the hair-pins cannot be bent laterally, as has been the custom. Furthermore, the extra weight unavoidable with hair-pins of such large section makes the mat clumsy to handle and causes excessive bending stresses

in the pivot pins when the mat is rolled up and lifted from its center or ends. If the pins once become bent, it is practically impossible to straighten same without taking the mat to pieces.

5 Probably the most important advantage of my construction is that the mat may be commercially manufactured for use with the above-described container. In this case it is extremely important that the width of the mat be maintained within close limits so that when the mat is laid in the container and pressed down, it will snap between the inclined walls 12 and be thereby held in position. The old-style mat could not be manufactured commercially within the desired limits and would for this reason be unsatisfactory when 10 15 used with a container.

20 Some changes may be made in the arrangement, construction and combination of the various parts of my improved mat construction without departing from the spirit of my invention and it is my intention to cover by my claims such changes as may reasonably be included within the scope thereof.

I claim as my invention:

1. In combination, a container having a relatively thin flat bottom and having an inwardly extending rim therearound, a mat adapted to snugly fit into said container, said mat comprising a plurality of rectangular shaped links having parallel openings in the respective ends of each 25 link, said links being assembled crosswise in rows with each link spaced from the adjacent links and with the ends of said links inserted between the links in the adjacent rows sufficiently that the openings in the interlocked end portions are 30 axially aligned, grommets disposed in the ends of each row of openings, tubular pins extending through each of said aligned rows of openings, around which said links pivot, the ends of said tubular member being flanged outwardly over 35 said grommets to prevent axial movement of said pins relative to said links, said flanged portions of said pins coacting with the rim of said container to resiliently retain said mat therein.

2. In combination, a container having a relatively flat bottom of molded rubber and having an inwardly extending rim therearound, a mat adapted to be resiliently secured in said container, said mat comprising a plurality of molded rubber rectangular shaped links having parallel 45 openings in the respective ends of each link, said links being assembled crosswise in rows with each link spaced from the adjacent links, and with the ends of said links inserted between the links in the adjacent rows sufficiently that the 50 openings in the interlocked end portions are axially aligned, tubular pivot pins extending through each of said aligned rows of openings around which said pins pivot, and a drive screw inserted in the ends of each of said tubular pins 55 which prevent axial movement of said pins relative to said links, the heads of said drive screws coacting with the rim of said container to resiliently retain the mat in said container.

3. In combination, a container having a relatively flat bottom of moulded rubber and having an inwardly extending rim therearound, a mat adapted to be resiliently secured in said container, said mat comprising of a plurality of moulded rubber rectangular-shaped links having 65 parallel openings in the respective ends of each link, said links being assembled crosswise in rows with each link spaced from the adjacent links, the ends of said links being inserted between the links in the adjacent rows sufficiently 70 75

that the openings in the inter-locked end portions are axially aligned, pivot pins extending through each of said aligned rows of openings, said pins being independently rotatable relative to each other, and a retaining device secured to each end of each pin, each of said retaining devices having a head which extends radially beyond the openings in said links and prevents axial displacement of said pins, and the heads of said devices coacting with the rim of said container to resiliently retain the mat in said container.

4. In combination, a container having a relatively flat bottom with an inwardly extending flexible rubber rim extending therearound, a mat adapted to be resiliently secured in said container by means of said rim, said mat comprising a plurality of links with pivot pins extending through suitable openings therein so as to form a flexible mat, the ends of said pins projecting from the edges of said mat sufficiently to co-act with said inwardly extending rim and thereby

resiliently retain said mat within said container.

5. In combination, a container having a relatively flat bottom of molded rubber with an inwardly extending flexible rubber rim extending therearound, a mat adapted to be resiliently secured in said container by means of said rim, said mat comprising a plurality of molded rubber rectangular-shaped links having parallel openings at the respective ends of each link, said links being assembled crosswise in rows with each link spaced from the adjacent link and with the ends of said links in each row being inserted between the links in the adjacent rows sufficiently that the openings in the interlocked end portions are axially aligned, pivot pins extending through each of said aligned rows of openings and means associated with the ends of said pins which prevent the withdrawal of the pins from said links, said means coacting with said rim to resiliently retain said mat in said container.
